CONTROL SYSTEM FOR CONTINUOUS CASTING

Temple W. Ratcliffe, Beaver, Pa., assignor, by mesne assignments, to The Babcock & Wilcox Company, Jersey City, N. J., a corporation of New Jersey

Application November 10, 1951, Serial No. 255,862

5 Claims. (Cl. 22—57.2)

The present invention relates to electrical control systems, and more particularly to control systems for the regulation of continuous metal casting units.

In the continuous casting of metals an open ended fluid cooled mold receives molten metal delivered to one end thereof and the casting is withdrawn from the opposite end. With the pouring means and the withdrawal mechanism properly coordinated, the molten metal level within the mold will remain in substantially the same position. Under these conditions the apparatus can be operated for maximum casting production within the cooling capacity of the mold. Ordinarily it is of advantage to maintain the withdrawal rate of casting from the mold at a substantially uniform value while the pouring means is manually or automatically controlled to maintain the molten metal level at a uniform position in the mold.

The casting withdrawal mechanism is usually motor driven and is subject to close speed control so that the casting withdrawal rate can be maintained at any desired uniform value. The pouring means may include a bottom pour or tilting type of pour vessel discharging molten metal to either a lip pour intermediate vessel, a trough or a tun dish, from which the molten metal is bottom poured into the casting mold. It is difficult to maintain a uniform pour rate from the pouring apparatus presently in use. Such difficulties may be caused by erosion or slag additions in the pouring vessels and when a tilting type pouring vessel is used, the geometry of molten metal container ordinarily prohibits the use of a uniform angular motion in the tilting mechanism of the vessel.

In accordance with my present invention, I provide a control apparatus actuated by movement of the molten metal level within the mold from a selected level. The control responds to the rise or fall of molten metal level within the mold to regulate the rate of molten metal delivered to the mold. When the controller is utilized to regulate the pour rate from a tilting type vessel, the control changes the tilting rate of the vessel in response to the deviation of the molten metal level from its desired control locations. When a controller is used with a bottom pour type of vessel, having a valve or the like therein, the controller opens or closes the valve in response to the change of molten metal level within the mold. This is accomplished by temperature measurements at the preferred molten metal level within the mold with the controller interpreting these readings to change the pouring rate correspondingly.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described an embodiment of my invention.

2

Of the drawings:

Fig. 1 is an elevation of a continuous casting apparatus incorporating the control of the present invention;

Fig. 2 is an enlarged elevation, in section, of a portion of the apparatus shown in Fig. 1;

Figs. 3, 4, 5 and 6 are fragmental elevation views, in section, showing different temperature sensitive devices installed in the wall of the mold shown in Fig. 2;

Fig. 7 is a schematic diagram of the control system; and

Fig. 8 is simplified wiring diagram of a portion of the control system shown in Fig. 7.

The present invention is illustrated in the drawings as applied to a continuous casting unit for steel and other high melting temperature alloys wherein the pouring means is of the lip-pour tilting type. However, it will be understood, the control method and apparatus herein-after described can be successfully used in casting metals having lower melting temperatures, or with pouring means of the bottom pour type wherein a valve is utilized to regulate the rate of metal flow from the pouring vessel.

As shown in Fig. 1, the metal pouring means includes a vessel 10 arranged for lip pouring, and a tun dish 11 arranged to receive molten metal from the vessel 10 and to deliver a substantially slag-free stream of metal to a selected position in the open upper end of a continuous casting mold assembly 12.

The vessel 10 is arranged for tilting movement about a transverse horizontal axis defined by trunnions 13 extending outwardly on opposite sides of an L-shaped frame 14 supporting the vessel. The trunnions are supported in trunnion bearings 15 each of which is mounted on a pedestal 16. The tilting movement of the vessel is obtained in a suitable manner, such as by means of a drum hoist 17 driven by a variable speed motor 18. The speed of the motor 18 is regulated by a control system herein-after described, and indicated generally at 19, in Fig. 1. The hoist 17 is connected to the vessel 10 by a cable 20 and a yoke 21 which is attached to the platform of the frame 14 supporting the vessel.

Beneath the mold 12, the casting 22 formed therein is engaged by a set of pinch rolls 23 driven by a variable speed motor 24. The casting leaving the mold 12 is subjected to the direct cooling effects of a water spray from a plurality of jets formed in the encircling manifold 25, and is restrained against transverse movement by guide shoes 26 or the like positioned in the space between the mold 12 and the pinch rolls 23.

The upper end portion of the casting mold assembly 12 is shown in Fig. 2. While in the mold assembly, the molten metal delivered thereto by the pouring vessel and tun dish, and the embryo casting formed therein are in contact with or adjacent to the inner surface of a water cooled vertically elongated metallic molding tube or liner 30 which is open at its upper and lower ends and is of the desired casting cross-section. The upper open end of the tube is supported in a top plate 31, whereby the tube is pendently supported from the fixed level of the plate and is free to expand axially therefrom. The plate forms the top wall of an annular chamber 32 defined by a cylindrical member 33 mounted on a load carrying bottom plate 34.

A metallic tubular skirt 35 of corresponding cross-sectional shape surrounds the mold liner and is arranged to confine a flow of cooling liquid against the surface of the mold liner substantially throughout its length. The skirt is also pendently supported at its upper end by attachment to the plate 34. Above the plate 34, a baffle 36 projects upwardly into the chamber 32 to cooperate with the liner 30 and plate 31 to define a discharge weir 38 from the chamber 32 into the water passage 40 provided between the liner 30 and skirt 35.

Cooling water inlets 41 open to the chamber 32 at uni-

form circumferentially spaced positions in the lower portion of the cylindrical member 33. The upper end or the weir 38 section is shaped to form an anti-cavitation entrance nozzle to the water passageway 40. This construction insures the flow of a uniform solid stream of cooling water into the entire circumference of the flow passageway 40. In addition, the converging entrance to the passageway provides for an acceleration of the water velocity to a rate, in the annular passageway 40, which will be within the range of turbulent flow, thus insuring a high rate of heat transfer from the outer face of the liner 30 to the cooling water.

With a substantially uniform pinch roll speed, it is desirable to control the pouring rate of molten metal delivered to the mold to maintain the level of molten metal substantially uniform, for example at the position indicated at B. This can be accomplished, in the manner hereinafter described, by the use of means for detecting the presence of molten metal at the desired level, or a variation of the actual molten metal level from the desired level, with the detecting means transmitting the actual molten metal surface level information to the controlling means. A variety of molten metal level detecting means can be used, whether actuated by penetrating radiation, radiant, electric contact or by temperature measurements of the embryo casting below or within the mold assembly. It will be understood that whatever detecting means are used, the apparatus should not deleteriously interfere in any marked degree with the cooling mechanism of the mold.

A change in the actual level of the molten level in the mold has been found to cause a measurable temperature change in the mold, i. e. a drop in the molten metal level below a predetermined position in the mold will cause a drop in the mold wall temperature sufficient to be detected by a temperature sensitive element such as a thermocouple imbedded in the mold at this initial predetermined position. Likewise an increase in the molten metal level will cause a detectable temperature rise on the thermocouple as the metal level passes the thermocouple position. Thus, it has been found that thermocouples or other temperature sensitive means imbedded in the mold wall can be used to detect the presence or absence of molten metal at selected positions within the mold, and such indications can be correlated to actuate a control mechanism to regulate the pour rate of metal to the continuous casting unit.

Temperature sensitive means for this purpose are inserted in the wall of the mold liner 30, as illustrated in Figs. 3, 4, 5 and 6. In Fig. 3 the temperature sensitive means consists of a series of thermocouples 44 imbedded at spaced longitudinal positions in the wall of the liner, with the cold junction ends 45 of each thermocouple positioned external of the mold in a zone of substantially uniform temperature and connected in series so that a variation in molten metal level between and intermediate the positions A, B and C, for example, will create corresponding detectable changes in the voltage generated by this series thermocouple, which changes can be utilized to regulate the pouring rate of molten metal delivered to the mold assembly 12.

The thermocouples illustrated in Fig. 4 are likewise connected in series, with, however, the cold junctions 46 thereof positioned adjacent the cold face of the mold liner wall. The thermocouple arrangements shown in Figs. 3 and 4 have proven to be practical for the detection of a change in the molten metal level within the casting mold, particularly when the mold wall thickness is relatively great, for example, approximating one half inch or more. I prefer however to use a resistance thermometer in the mold wall, such as illustrated in Figs. 5 and 6, since such temperature sensitive means employ fewer connections, and are simpler to install and maintain in an operative condition.

As shown in Fig. 5, a platinum resistance element 47 is imbedded in the mold liner wall with the lead wires there-

from extended upwardly through the wall, and connected with the controller, as hereinafter described. In Fig. 6, the temperature sensitive element consists of a segment 48 of the mold liner wall having lead wires extending from opposite ends of the segment upwardly through the wall and likewise connected with the controller.

The installation of the temperature sensitive elements in the mold liner wall can be conveniently accomplished by cutting a suitable keyway-like groove longitudinally in the cold face of the mold, inserting the elements with their connecting leads, and placing a flat key in the cold surface side of the mold which is soldered in position with the outer wall surface and thereafter refinished to provide a smooth surface for the flow of cooling water thereover.

It will be noted the mold wall hot face temperature does not exceed 450° F., even though the molten metal in contact with the hot face of the mold will initially be at a temperature as high as 3000° F. This is due to the high efficiency of the mold cooling system utilized in the described casting unit.

The electric energy transmitted through the lead lines from the temperature sensitive element is impressed on a measuring circuit which includes a slidewire drive motor. The slidewire drive motor is positioned by the circuit which is operated on the well known "null balance principle" wherein an unknown resistance is measured by comparing it with an adjustable resistance. As shown in Fig. 5 an adjustable resistance R is adjusted to a value closely equal to the resistance of the platinum resistance element 47 when the molten metal level in the mold is in a desired position, for example, at the position represented by the symbol B.

A simplified wiring diagram of a typical measuring unit using the null balance principle is illustrated in Fig. 8. As shown, S represents the bridge electric supply; T the resistance of the platinum element 47; R the manually adjustable, and F and G fixed, resistors; and M the slidewire motor. The electric amplifier and motor control M. C. regulates the operation of the reversible slidewire motor M to continuously balance the circuit in accordance with the changes of temperature in the resistance of the element 47. As shown in Fig. 5, the adjustable resistance R is positioned adjacent the mold assembly 12.

It will be appreciated the slidewire drive motor of the measuring unit could be directly connected with, or through suitable power amplifying means to, an adjustable rheostat in the speed control circuit of the pouring means rate control. Such a control arrangement would be of the modulating type and would increase or decrease the pour rate substantially immediately in response to changes in the molten metal level within the casting mold. This type of control is, however, subject to "hunting" and is difficult to maintain in an operative condition. I prefer to utilize a pair of measuring units which are alternately connected in timed sequence with the temperature sensitive means, with each slidewire drive motor in turn transmitting rotational movement to a differential gear mechanism in response to the unbalance between the resistances T and R. Simultaneously the other slidewire motor is transmitting rotational movement to the differential gear in accordance with the unbalance between the resistance measured at the end of the previous period of connection with the temperature sensitive element.

The arrangement of equipment to accomplish this control sequence is illustrated in Fig. 7. As shown in the drawing, the measuring units X and Y, with their control circuits such as illustrated in Fig. 8, are each provided with a shaft 51 and 52 respectively driven by the slidewire motor and connected with a differential gear 53. The output shaft 54 from the differential gear is connected with a rheostat in the motor speed control circuit 75 49 of the hoist 17.

The lead wires 50 from the resistance element 47 in the mold liner wall 30 are connected with the measuring unit X, and a set of branch wires 56 join the wires 50 with the measuring unit Y, so that the units X and Y are electrically connected in parallel. A separate set of wires 57 and 58 connect the units X and Y in parallel with a source of electricity Z. Each set of wires connected with the units X and Y are provided with contact switches 1B, 1C, 1D, and 1E, all of which are gang operated by a magnetic coil 1. Switch contacts 1B and 1E are closed when 1C and 1D are open, i. e. when the coil 1 is deenergized. When coil 1 is energized, contacts 1B and 1E are open and 1C and 1D are closed.

The coil 1 is alternately energized and deenergized in a timed sequence by the operation of the timers CCA and CCB in the timing control circuit illustrated in Fig. 7. As shown, the circuit is in the dead board position. Energizing the circuit, energizes coil 1, closes contact 1A, and thereby reverses contacts 1B, 1C, 1D and 1E from the position shown, so that the measuring unit X is connected with the element 47 and resistance R, while Y is connected with the source of energy Z. Closing the contact 1A starts the timer CCA. At the end of the desired time period the timer CCA causes the contact A' to close, energizing coil 2 and reversing contacts 2A, 2B and 2C.

Opening contact 2A deenergizes coil 1 to reverse the contacts 1A, 1B, 1C, 1D and 1E, to the position shown in Fig. 7. With 1A open, timer CCA is automatically reset and ready to operate for a timed period when the set period of operation has elapsed on timer CCB. Closing contact 2C starts timer CCB which will operate for a set period of time until at the end of the timed period of operation on CCB the contacts B' momentarily open to deenergize coil 2 and to again reverse contacts 2A, 2B and 2C (i. e. to the position shown in the drawing). Thereafter, the cycle of timer operation is repeated.

In operation, the resistance R is adjusted to a value equal to the resistance T when the molten metal level within the mold is at the desired position. For example, when the molten metal is at the position B of Fig. 5 the resistance T of the resistance element 47 should equal the resistance R, which is common to both of the units X and Y. Thus, when the actual molten metal level is above or below the position B the resistance of the element 47 will change and the value of the resistance T in the modified Wheatstone bridge circuit will operate the motor M in one of the units X and Y, shifting the position of the slide wire to balance the circuit. The direction of rotation of the motor M will depend upon whether the resistance T is greater or lesser than that of the resistance R, i. e. whether the actual molten metal level is above or below the desired position B.

In the control circuit shown (see Fig. 8), the slide-wire contact H will be at its midpoint when the resistances T and R are equal, i. e. when the molten metal level is at its desired position within the mold. A change in the molten metal level will cause a proportional change in the resistance of the element 47 and an unbalance in the measuring unit with the slide-wire motor moving the contact H to balance the circuit. Movement of the contact H simultaneously causes rotational movement of the shaft of the slide-wire motor and of one side of the differential gear 53. At the same time the shaft of the other measuring unit will be rotating due to the return of the slide-wire contact H thereof to its midpoint by reason of an equal flow of energy through the resistors F and G of the measuring unit.

As an example of the operation of the control system described, it will be assumed the molten metal level had dropped to a position approximating C, as shown in Fig. 5. Under these circumstances, the control would act to increase the delivery rate of molten metal to the continuous casting mold. Let it further be assumed that the un-

balance on the measuring unit X at the end of this timed period, during which unit X was connected with the element 47, can be represented by the number +16. The number 16 is an arbitrary unit selected for purposes of illustration and may represent the number of revolutions made by the shaft 51 while the sign + or - indicates the direction of movement, with + indicating a direction tending to increase the rate of metal delivery to the mold. If it is further assumed the level had been maintained at the desired position during the preceding measuring period, the contact H of unit Y would be at its midpoint and the shaft 52 would not move under the influence of Z during this period. Thus, the net effect on the shaft 54 would result in an increase in the speed of the hoist motor 18 equivalent to the +16 movement of the shaft 51.

During the next or second timed period, the unit X is connected with the element Z, with the slide-wire contact H returned to its midpoint with shaft rotation from +16 to 0 by the influence of Z. At the same time the measuring unit Y will be responding to the position of the molten metal level in the mold. Although the control system will have greatly increased the delivery rate of molten metal to the mold the molten metal level will still be low and will not reach the position B. Thus at the end of the timed period the unit Y will retain a +8 value, for example. The net effect of the movement of the shafts 51 and 52 on the shaft 54 will be -8, since the return from +16 to 0 on the shaft 51 will be in a negative direction i. e. -16, and the movement of the shaft 52 will be in a position direction i. e. +8.

During the next or third timed period the shaft 52 will return from +8 to 0 under the influence of Z, with rotation in a negative direction equal to -8 units. At the same time, with the unit X connected with the temperature sensitive element 47, the shaft 51 rotates in proportion to the deviation between the actual molten metal level and the position B. If the actual metal level is still low the shaft 51 will rotate in a positive direction, for example +4, with the net result of a -4 rotation on the differential output shaft 54 (-8+4=-4). Alternately, if the actual metal level is actually higher than the desired position B, the shaft 51 will rotate in a negative direction. If this value is, for example, -4 the net result on the rotation of the output shaft will be the addition of the -8 units from the unit Y plus the -4 units from the unit X, or a net of -12 units. Such a condition would of course indicate that the rate of pour was excessive and the pouring rate would be reduced an amount proportional to the -12 units delivered to the rheostat hoist motor control.

While in accordance with the provisions of the statutes I have illustrated and described herein a preferred embodiment of the invention, those skilled in the art will understand that changes may be made in the method of operation and form of the apparatus disclosed without departing from the spirit of the invention covered by my claims, and that certain features of the invention may sometimes be used to advantage without a corresponding use of other features.

I claim:

1. Continuous casting apparatus including a fluid cooled mold, power means for regulating the rate of delivery of molten metal to said mold, means adapted to withdraw the casting from said mold, a thermo-sensitive element associated with said mold and adapted to respond to changes in the position of the molten metal level within the mold by a change in electric flow from said thermo-sensitive element, and speed control means responsive to said changes in electric energy flow to regulate the rate of molten metal delivery to said mold comprising a slide-wire motor adapted to compare the electric flow from said thermo-sensitive element with an electric flow standard and to cause mechanical movement proportional to the difference between said energy flows, and an opera-

tive connection between said slidewire motor and said power means to regulate the speed of the latter in response to the movement of the former.

2. Continuous casting apparatus including a mold, power means for regulating the rate of delivery of molten metal to said mold, means adapted to withdraw the casting from said mold, a resistance thermometer positioned to respond to changes in the position of the molten metal level within the mold from a selected level by a change in electric voltage flow, and speed control means responsive to said changes in electric voltage flow to regulate the rate of molten metal delivery to said mold comprising a pair of slidewire motors alternately connected with said thermo-sensitive element and with a standard source of electric voltage flow, the voltage flow from said resistance thermometer causing a slidewire motor movement proportional to the difference between the actual and selected molten metal levels within the mold while the voltage flow from said standard source causes the other slidewire motor to return to a position equivalent to the selected mold metal level, and a conjoint connection between said slidewire motors and said power means.

3. Continuous casting apparatus including a fluid cooled mold, a pouring vessel for delivering molten metal to one end of said mold, power driven means for regulating the pouring rate of molten metal from said pouring vessel, means for withdrawing the continuous casting from the opposite end of said mold, means sensitive to changes in the actual molten metal level within said mold from a selected position, and speed control means operatively connected with the power driven means of said pouring vessel and said molten metal level sensitive means for regulating the rate of molten metal delivery to said mold comprising a pair of measuring elements operable in proportional response to said changes in molten metal level from a selected position in the mold, a timer control system alternately connecting each of said measuring elements with said metal level sensitive means while the other of said measuring elements is connected to modify the proportional response of said first measuring element, and means for combining the proportional responses of both of said measuring elements to regulate said power driven means.

4. In combination with a continuous casting mold, a pouring vessel for delivering molten metal to one end of said casting mold, a variable speed motor drive to regulate the pouring rate from said vessel, means for withdrawing an embryo casting from the opposite end of said

mold, detecting means associated with said fluid cooled mold whereby a change in the molten level within said mold causes a change in voltage output from said detecting means, a pair of slidewire motors associated with 5 Wheatstone bridge circuits connected with said detecting means to compare the voltage output therefrom with an adjustable standard voltage, a shaft connected with each of said slidewire motors and with a differential gear, the output shaft of said differential gear connected with a 10 speed control rheostat in the variable speed motor drive circuit of said pouring vessel, and a timing circuit for alternately connecting each of said slidewire motors with said detecting means while the companion slidewire motor is connected with a standard adjustable voltage source 15 of electricity.

5. In combination with a continuous casting mold, a pouring vessel for delivering molten metal to one end of said casting mold, a variable speed motor drive to regulate the pouring rate from said vessel, means for withdrawing an embryo casting from the opposite end of said mold, temperature sensitive means positioned in the wall of said fluid cooled mold whereby changes in the molten metal level within said mold causes a change in the voltage output from said temperature sensitive means, 20 a pair of slidewire motors associated with Wheatstone bridge circuits connected with said temperature sensitive means to compare the voltage output therefrom with an adjustable standard voltage, a shaft connected with each of said slidewire motors and with a differential gear, the 25 output shaft of said differential gear connected with a speed control rheostat in the variable speed motor drive circuit of said pouring vessel, and a timing circuit for alternately connecting each of said slidewire motors with said temperature sensitive means while the companion 30 slidewire motor is connected with a standard adjustable voltage source of electricity.
